Primary Examiner — Elizabeth J Oswecki(74) *Attorney, Agent, or Firm* — Foley & Larnder LLP(57) **CLAIM**

We claim the ornamental design for a semiconductor device, as shown and described.

DESCRIPTION

FIG. 1 is a perspective view of a semiconductor device showing our new design;

FIG. 2 is a top view thereof;

FIG. 3 is a bottom view thereof;

FIG. 4 is a front elevation view thereof;

FIG. 5 is a rear elevation view thereof;

FIG. 6 is a right side elevation view thereof; and,

FIG. 7 is a left side elevation view thereof.

The broken lines shown in the drawings represent portions of the semiconductor device that form no part of the claimed design.
